APPARATUS FOR THE TREATMENT OF SLURRIES OF CHEMICAL REAGENTS

Elmer R. Burling and John P. Rich, Nashua, N. H.

Application October 19, 1951, Serial No. 252,122

4 Claims. (Cl. 23—260)

It is an object of this invention to provide a method and apparatus for carrying out large scale chemical reactions where the reagent is either corrosive, explosive or both. Specifically this has reference to bleaching wood pulp with chlorine dioxide as set forth in our copending application Serial No. 252,121, filed of even date herewith and now Patent No. 2,706,673, dated April 19, 1955.

It is a further object of this invention to provide a method and apparatus as aforesaid in which a minimum portion of the apparatus is brought in contact with the reagent.

It is a further object of this invention to provide a method and apparatus as aforesaid in which migration of the reagent in active condition beyond predetermined limits is absolutely prevented.

The above and other objects will be made clear from the following detailed description taken in connection with the annexed drawings in which:

Fig. 1 is a front elevation of the improved apparatus partly in section; and

Fig. 2 is a side elevation also partly in section.

The essential elements of the apparatus are a compacting tower 12, a thick stock pump 14, a particularly designed line 16 connecting the stock pump with a mixer 18. Stock leaves the mixer 18 through a line 20 to the base of a primary reacting tower 22. At the top of the primary reaction tower 22 a line 26 connects it to a secondary reacting tower 28. The base of the secondary reacting tower 28 has formed therein a cone 32. A pair of agitating impellers 34 are provided between the cone and the inner wall of the tower 28. A number of inlet pipes 36 are brought through the wall of the tower 28 adjacent the apex of the cone while a pump 38 serves continuously to remove dilute stock from the bottom of the tower 28.

As illustrated pulp is delivered to the compacting tower 12 by a stock thickener 10 but the thick stock might be obtained from any other source.

The line 16 between the pump 14 and the mixer 18 is calculated as to length and diameter so that stock moving through it will form a plug seal against any migration of reagent backward from the mixer. The inlet pipes 36 in the tower 28 serve not only to dilute the stock for handling by the pump 38 but also to supply a neutralizing agent which will thoroughly overcome any corrosive or explosive effect of any residual reagent. Accordingly only the mixer 18, the primary reaction tower 22, the line 26 and the secondary reaction tower 28 need to be protected from corrosion.

Gases may be bled from the top of the tower 28 through a valve 40 and preferably are conducted to a cooler or condenser 42 where vapor and corrosive gases are condensed and the gases are redissolved so that the solution thus obtained may be returned to the system and the venting of corrosive gases avoided.

For purposes of heating and dilution steam may be

2

added to the stock in the compacting column 12 or to the mixer 18 or both. In the case of certain types of very sensitive reagents it is desirable to have the stock very uniformly heated in which case it will be best to do the heating in the compacting tower 12. As an alternative, steam may be added to the primary reaction tower 22 at a level where a sufficient amount of the reagent has been consumed.

It will be seen that due to the height of the primary reacting tower 22 and the friction of stock flowing through this column the stock in the mixer is under a very substantial pressure. This is especially desirable when the reagent such, for example, as chlorine dioxide is volatile or only slightly soluble at atmospheric pressure. Actually the pressure gradually decreases as stock moves up through the tower 22. Then in the tower 28, once the tower is full, incoming stock moving downwardly is subjected to gradually increasing pressure.

All of the towers and the line 26 have unobstructed interiors so that relatively high density stock can pass through. In general the cross-sectional area of the tower 28 will be from 10 to 20 times that of the primary tower 22. This means that the reaction time in the tower 28 has the same ratio to the reaction time in the tower 22. In many cases the reaction will be 80 percent complete by the time the stock leaves the line 26. The vastly greater reaction time in the tower 28 will usually be ample substantially to exhaust the reagent.

We claim:

1. Apparatus for reacting a high density aqueous slurry of wood pulp with a volatile, corrosive reagent such as chlorine dioxide comprising: a thick stock pump for advancing a high density slurry; a mixer; a conduit connecting said pump to said mixer, said conduit being proportioned with reference to the delivery of said pump so as to form a gas tight plug of stock between the pump and the mixer; means for supplying a solution of volatile, corrosive reagent to said mixer; a primary vertical reaction tower receiving, at its base, a mixture of said slurry and said reagent from said mixer; a secondary vertical reaction tower; a conduit connecting the tops of the two towers whereby to deliver said slurry mixture from the primary tower to the secondary tower; said secondary tower having adjacent its base a plurality of nozzles for diluting the slurry mixture and an outlet for removing all of the dilute slurry mixture from the system at the base of the secondary tower.

2. Apparatus as set forth in claim 1 in which the secondary tower has a volume from 10 to 20 times the volume of the primary tower.

3. Apparatus as set forth in claim 1 in which both towers have uninterrupted cross section.

4. Apparatus as set forth in claim 3 in which the secondary tower has a volume from 10 to 20 times the volume of the primary tower.
